UNITED STATES PATENT OFFICE

152,489

DESIGN FOR A DRIP CATCHER FOR A BOTTLE

Doris E. O'Brien, Billings, Mont.

Application October 17, 1946, Serial No. 134,005

Term of patent 7 years

(Cl. D58—26)

To all whom it may concern:

Be it known that I, Doris E. O'Brien, a citizen of the United States, residing at Billings, in the county of Yellowstone and State of Montana, have invented a new, original, and ornamental Design for a Drip Catcher for a Bottle, of which the following is a specification, reference being had to the accompanying drawing, forming part thereof.

The figure is a perspective view of a drip catcher for a bottle, showing my new design.

The rear portions of my design are substantially the same as the front visible areas.

I claim:

The ornamental design for a drip catcher for a bottle, as shown and described.

DORIS E. O'BRIEN.
